(57) **CLAIM**

The ornamental design for a display stand, as shown and described.

DESCRIPTION

FIG. 1 shows a perspective view of a display stand;

FIG. 2 shows a front view thereof;

FIG. 3 shows a rear view thereof;

FIG. 4 shows a right side view thereof;

FIG. 5 shows a left side view thereof;

FIG. 6 shows a top plan view thereof; and,

FIG. 7 shows a bottom plan view thereof.

The shade lines in the Figures show contour and not surface ornamentation.

The broken lines shown in the Figures show portions of the display stand which form no part of the claimed design.

1 Claim, 4 Drawing Sheets
